UNITED STATES PATENT OFFICE.

WALTER W. UPINGTON, OF TACOMA, WASHINGTON.

RAZOR-BLADE SHARPENER.

Application filed April 2, 1926. Serial No. 99,385.

The present invention is concerned with the provision of a sharpening device, and in its broader aspects comprehends supporting and rocking mechanism for an object to be sharpened, which may find a wide and varied range of usefulness in the arts. In a preferred embodiment of the invention, the device is utilized for sharpening razor blades, such for instance as blades of the ordinary Gillette or Durham duplex type.

An object of the invention is to provide a blade carriage which may be associated with a conventional type of strop, and reciprocating along the strop to effect sharpening of the blade.

A feature of the invention is the provision of a blade sharpener in which the blades are always held at an angle to the transverse plane of the strop, so that the desirable drawing off action commonly employed by barbers will be had.

A further feature of the invention is the provision of a blade holder from which blades may be readily removed and replaced, and which will facilitate the rapid turning over of the blades for sharpening opposite sides thereof.

Other objects of the invention are to provide a blade sharpening unit of simple, practical construction, which will be rugged, durable and efficient in use, and which may be manufactured with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a top plan view of a blade sharpener embodying the present invention, showing the same in operative relation to a strop or sharpening element.

Fig. 2 is a view in side elevation of Fig. 1.

Fig. 3 is a longitudinal sectional view on the line 3—3 of Fig. 1 with the strop removed.

Fig. 4 is a transverse sectional view on the staggered line 4—4 of Fig. 1.

Fig. 5 is an enlarged sectional detail of one end of the blade holder.

Fig. 6 is a perspective view of a modified type of sharpening unit in which the strop

ping element is in the nature of an endless belt contained within the unit.

Fig. 7 is a perspective view of the sliding cam plate which controls the rocking of the blade holder.

In the form of the invention shown in Figs. 1 to 5 and 7, the sharpener includes a blade holding unit adapted to be associated with a conventional strop 10 and manually reciprocated back and forth along the strop to effect sharpening of the blade. The blade holding unit may include a casing 11 open at its top. The side plates 12 of the casing are connected near their upper corners by rollers 13 under which the strop 10 is passed. The strop is threaded under one roller 13, over the face of a sliding cam plate 14, and under the face of the other roller, so that the cam plate is frictionally engaged by the strop.

Cam plate 14 has a limited sliding movement on suitable guide ways or platforms 15 projecting inwardly from the side walls 12 of the casing 11. The movement of the cam plate is limited by the engagement of a blade to be sharpened with the sharpening strop 10, as will be later described. As shown, these guide ways may be conveniently formed as inwardly presented flanges carried by knurled handle plates 16 riveted or otherwise secured at 17 to the outer faces of the side walls. These plates afford roughened thumb and finger receiving portions which may be grasped as the blade holding unit is manually reciprocated over the strop. Integral or rigid with the casing walls 12 are a pair of upwardly presented apertured ears 18 and 19 which receive trunnions 20 at the ends of a blade supporting plate member 21, whereby the plate member 21 is rockably mounted in the ears.

Plate member 21 is formed with lugs 22 adapted to enter the usual apertures in a Gillette blade indicated at 23. A clamping plate 24 is hinged as at 25 to one end of the plate 21 and co-operates with the plate 21 to hold the blade 23 in place. Preferably a plate 24 is formed with apertures 26 adapted to register with the lugs 22. The free end of clamping plate 24 is formed with a tongue 27 adapted to be locked under a locking yoke 28 pivoted as at 29 to the opposite end of the plate 21. As best seen in Figs. 4 and 5, this yoke may be swung outwardly to permit movement of the plate 24.

toward or away from blade clamping position, and swung inwardly over the tongue 27 to lock the clamping plate 24 against movement on its pivot 25.

It will be noted that the blade holder 21, 24 is angularly disposed relative to the transverse axis of the casing 11 and the strop 10, so that as the blade edges are brought into contact with the strop, the strop will sharpen them by the drawing off action or angular sliding action which is considered the most efficient for sharpening purposes.

Operative connections are provided between the cam plate 14 and the blade holder 21, 24 to effect reversal of the blade holder when the direction of relative movement of the casing 11 and strop 10 are reversed. As best seen in Fig. 7, the plate 14 is provided on each side with upstanding flanges 30. These flanges are each formed at one end with a cam groove 31 adapted to co-operate with a cam bar 32 carried by the blade holding plate 21. Preferably the grooves 31 are of arcuate shape and the under faces of the ends of the cam bars 32 are curved at 33 in accordance with the curvatures of the grooves 31. Since the blade holder is angularly disposed relative to the transverse plane of the cam plate 14, the cam grooves 31 are not opposite each other, but are arranged near opposite ends of their respective flanges 30.

The operation of the device is substantially as follows. Before the blade is placed in the holder, the casing 11 is mounted upon the strop 10 by threading the strop under the rollers 13 and over the cam plate 14 in the manner above described. The locking yoke 40 is then swung to the dotted line position of Fig. 5. Clamping bar 24 is swung on its pivot to permit a blade to be laid upon the plate 21 with its apertures receiving the lugs 22. The clamping plate is then swung down and locked by the yoke 28. The handle pieces 16 of the casing are then grasped and manually reciprocated to slide the casing back and forth along the strop 10, one end of which will be anchored or hung on a suitable support in the customary manner. As the casing moves in one direction relative to the strop, the frictional engagement between the strop and the cam plate 14 will tend to retard the cam plate, and upon such relative movement of the cam plate and casing the curved walls of notches 31 cam against the curved ends of the two cam bars 32 to tilt them as shown in Fig. 3, and consequently to rock the blade holder, and swing one edge of the blade against the strop. The angularity of the working faces of the cam grooves 31, 31 is such that a wedging action is provided between the face of the cam and the ends of the cam bars 32 to oscillate the blade holder. It will be noted that as the

blade holder is oscillated, one edge of the blade is moved against the strop, the wedging action between the cam groove and cam bars serving to force the blade to be sharpened against the strop with sufficient friction to limit the sliding movement of the cam plate on the rails.

Upon a reverse movement of the casing relative to the strop, the frictional engagement between the cam plate and strop will cause the plate to slide in the other direction relative to the casing, and the position of the blade holder from being reversed to press the opposite edge of the blade against the strop.

In Fig. 6 I have illustrated a modification in which an endless band 40 is substituted for the strop 10, this band running over rollers indicated in dotted lines 41 within the casing 42, and one of the rollers carrying an operating crank handle 43. The blade holder mechanism, cam plate etc., are the same as described above, and by reversing the direction of rotation of the crank handle, the blade holder will be reversed as will be readily understood.

Various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. In a sharpener of the class described, stropping means and blade holder supporting means movable relative to each other, a tilting blade holder on the supporting means disposed at an angle to the transverse axis of the stropping means, means operable upon relative movement of the stropping means and blade holder supporting means, to swing one edge of a blade in the holder against the stropping means, whereby the desired drawing off sharpening action is had, and means compelling reverse tilting of the blade holder when the direction of relative movement of the blade holder supporting means and stropping means is reversed, the reverse tilting means including a cam plate slidably mounted in the blade holder supporting means and shiftable by its frictional engagement with the stropping means.

2. In a sharpener of the class described, stropping means and blade holder supporting means movable relative to each other, a tilting blade holder on the supporting means disposed at an angle to transverse axis of the stropping means, means operable upon relative movement of the stropping means and blade holder supporting means, to swing one edge of a blade in the holder against the stropping means, whereby the desired drawing off sharpening action is had, means com-

10 pelling reverse tilting of the blade holder when the direction of relative movement of the blade holder supporting means and stropping means is reversed, the reverse tilting means including a cam plate slidably mounted in the blade holder supporting means and shiftable by its frictional engagement with the stropping means, and cam fingers rigid with the blade holder rocked by cams on the plate.

15 3. A razor blade sharpener including a strop, a blade holder support connected to the strop for sliding movement relative thereto, a blade holder rockably mounted in the support, a cam plate slidable in the support and shifted by its frictional engagement with the strop, operative connections between the cam plate and blade holder for rocking the blade holder to reverse the blade 20 as the cam plate slides relative to the support.

25 4. A razor blade sharpener including a strop, a blade holder support connected to the strop for sliding movement relative thereto, a blade holder rockably mounted in the support, a cam plate slidable in the support and shifted by its frictional engagement with the strop, operative connections between the cam plate and blade holder for 30 rocking the blade holder to reverse the blade as the cam plate slides relative to the support, said connections including grooved flanges on the cam plate and cams on the holder working in the grooves.

35 5. A razor blade sharpener including a strop, a blade holder support connected to the strop for sliding movement relative thereto, a blade holder rockably mounted in the support, a cam plate slidable in the sup-

40 port and shifted by its frictional engagement with the strop, operative connections between the cam plate and blade holder for rocking the blade holder to reverse the blade as the cam plate slides relative to the support, said connections including grooved 45 flanges on the cam plate and cams on the holder working in the grooves, the engagement of the blade and strop limiting the sliding movement of the cam plate.

50 6. The combination with an open topped casing, of a cam plate sliding in guideways below the top thereof, a blade holder rockably mounted in bearings at the top of the casing and including a pair of blade clamping elements, rollers at the end of the casing 55 under which, and over the cam plate, a strop is adapted to be threaded, and operative connections between the cam plate and the blade holder, whereby when the cam plate is slid by its frictional engagement 60 with the strop, the blade holder will be tilted.

65 7. The combination with an open topped casing, of a cam plate sliding in guideways below the top thereof, a blade holder rockably mounted in bearings at the top of the casing and including a pair of blade clamping elements, rollers at the end of the casing under which, and over the cam plate, a strop is adapted to be threaded, and operative 70 connections between the cam plate and the blade holder, whereby when the cam plate is slid by its frictional engagement with the strop, the blade holder will be tilted, said means including flanges on the cam plate 75 having recesses therein and cams rigid with the holder working in the grooves.
